MUFFLER

Carl Peters, St. Louis, Mo.

Application March 11, 1946, Serial No. 653,661

8 Claims. (Cl. 181—53)

1

This invention relates generally to mufflers, or silencers, and more specifically to devices of this type which are adapted for use in silencing the noises resulting from the operation of internal combustion engines, the predominant object of the invention being to provide a muffler of the type mentioned which, because of its improved construction and arrangement, is capable of performing its intended function in an improved and highly efficient manner.

Fig. 1 is a perspective view of the improved muffler of the present invention.

Fig. 2 is a horizontal section on an enlarged scale which is taken through the muffler shown in Fig. 1.

Fig. 3 is a longitudinal section taken on the staggered line 3—3 of Fig. 2.

Fig. 4 is a cross-section taken on line 4—4 of Fig. 2.

Fig. 5 is an enlarged, fragmentary, longitudinal section taken on line 5—5 of Fig. 2.

In the drawing, wherein is shown for purposes of illustration, merely, one embodiment of the invention, A designates the improved muffler generally. The muffler A comprises an outer housing 1 which preferably is slightly tapered longitudinally thereof so as to minimize the resistance of air to the muffler when same is in motion on a moving vehicle. In cross-section the outer housing 1 of the muffler A is shaped as is shown in Fig. 4, and said outer housing includes an end member 2 which closes one end of said outer housing, and an end member 3 which closes the opposite end of said outer housing. The end member 2 is provided with a marginal flange 2', and the end member 3 is provided with a similar marginal flange 3', said marginal flanges 2' and 3' overlapping and embracing opposite end portions of the wall of the body portion of the outer housing of the muffler and said marginal flanges being welded, or otherwise secured to said wall of said body portion of the outer housing so as to secure the end members 2 and 3 in place with respect to the body portion of the outer housing. The end member 2 has formed thereon, or fixed thereto, a tubular inlet element 4 which communicates with the interior of the outer housing of the muffler, and the end member 3 has formed thereon, or fixed thereto, a tubular outlet element 5 which also communicates with the interior of the outer housing of the muffler.

Arranged within the outer housing 1 of the muffler A is a plurality of partitions which serve to divide the interior of said outer housing into a plurality of passageways. The plurality of par-

2

titions referred to include a partition 6 and a partition 7 which are provided with inner end portions 6' and 7' which are curved toward each other and meet at the point designated by the reference character 8 in Fig. 1 in abutting relation, said abutting ends of said curved portions 6' and 7' of the partitions 6 and 7 being welded, or otherwise secured together. At the ends of the partitions 6 and 7 opposite to the ends thereof which are curved toward each other, said partitions are provided with flanges 9 and 10 which contact with the inner face of the end member 2, and which are welded or otherwise secured to said end member 2. Also, the partitions 6 and 7 are provided with flanges 11 and 12 at the tops and bottoms thereof, as is shown to good advantage in Fig. 4, which contact with the inner faces of the upper and lower walls of the body portion of the outer housing 1 of the muffler A, said flanges being secured to said upper and lower walls of said body portion of the muffler, preferably by being welded thereto.

Interposed between the partitions 6 and 7 is a partition 13 which is provided with flanges 14 and 15 at its opposite ends, the flange 14 being secured to the inner face of the end member 2 and the flange 15 being secured to the inner face of the curved portion 7' of the partition 7. Preferably, the flanges 14 and 15 of the partition 13 are secured to the end member 2 and the curved portion 7' of the partition 7 by being welded thereto, and, also, the partition 13 is provided with flanges 16 at its top and bottom which are secured to the inner faces of the upper and lower walls of the body portion of the outer housing of the muffler A. The plurality of partitions, which are referred to above as being located within the outer housing of the muffler A, includes a partition 17 which is interposed between the partition 6 and a curved side wall of the outer housing of the muffler, said partition 17 being provided with a flange 18 at its forward end which is secured to the inner face of the end member 2, preferably by being welded thereto. The opposite end of the partition 17 is secured by welding, or otherwise, to the end member 3, and said partition 17 is provided with flanges 19 at its top and bottom which are secured to the inner faces of the upper and lower walls of the body portion of the outer housing of the muffler.

By referring to Fig. 2 it will be noted that the partition 6 is imperforate throughout its length, and that the partition 13 has formed therethrough a multiplicity of spaced apertures 20 which extend throughout the entire length and

width of said partition 13. Also, it will be noted that the partition 7 is imperforate throughout its length except for a row of apertures 21 formed therethrough which are located immediately adjacent to the end member 2, and that the partition 17 has formed therethrough a multiplicity of spaced apertures 22 which extend throughout the entire length and width of said partition 17. It will be noted, also, by referring to Fig. 2, that because of the arrangement of the partitions 6, 7, 13, and 17 a plurality of passageways are provided within the outer housing 1 of the muffler A; there being a passageway 23 between the partitions 6 and 13, with which the inlet element 4 communicates, a passageway 24 between the partitions 1 and 13 which is placed in communication with the passageway 23 by the apertures 20 of the partition 13, a passageway 25 between the partition 7 and an adjacent side wall of the outer housing 1 of the muffler, a passageway 26 between the partitions 6 and 17, a curved passageway 27 between the curved inner end portions 6' and 7' of the partitions 6 and 7 and adjacent portions of the outer housing of the muffler which places the passageways 25 and 26 in communication with each other, and a passageway 28 between the partition 17 and an adjacent side wall of the outer housing of the muffler which is placed in communication with the passageway 26 by the apertures 22 of the partition 17, and with which passageway 28 the outlet element 5 communicates.

In assembling the improved muffler, the partitions 6, 7, 13, and 17 are welded to the inner face of the end member 2 at the flanges 9, 10, 14, and 18 of said partitions, the ends of the curved portions 6' and 7' of the partitions 6 and 7 being welded in abutting relation, and the inner end of the partition 13 being welded to the curved portion 7' of the partition 7 at the flange 15 of said partition 13. The partitions 6, 7, 13, and 17 of the assembled partitions and end member 2, are then introduced into the outer housing 1 of the muffler, which has the end member 3 welded in place with respect thereto, and the assembly is moved longitudinally of said outer housing until the flange 2' of the end member 2 reaches a position where it embraces the forward end portion of the wall of the body portion of the outer housing of the muffler. The upper and lower walls of the body portion of the outer housing of the muffler have formed therethrough a multiplicity of apertures 29 which are so located and arranged that said apertures are spaced longitudinally of the flanges 11, 12, 16, and 19 of the partitions 6, 7, 13, and 17, and welds 30 (see Fig. 5) are formed in the apertures 29 which secure the flanges of said partitions to the walls of the apertures. The flange 2' of the end member 2 is welded to the wall of the body portion of the outer housing of the muffler, and the rear edge of the partition 17 is welded, or otherwise secured, to the inner face of the end wall 3 of the outer housing of the muffler through the outlet element 5 whereupon the muffler is completely assembled and ready for use.

In the operation of the improved muffler, exhaust gases, issuing from an internal combustion engine with which the muffler is associated for use, are discharged into the muffler through the inlet element 4 in the form of successive pressure pulsations and accompanying sound waves. The gases and sound waves entering the muffler pass into the passageway 23 and pass therefrom through the multiplicity of apertures 20 formed

through the partition 13, into the passageway 24, said gases and sound waves being divided into a great number of parts because of their passage through said apertures 20. In the passageway 24 the direction of travel of the gases and sound waves is reversed, and various parts of the divided gases and sound waves are compelled to travel longer distances than other parts of the divided gases and sound waves, to reach and pass through the apertures 21 formed through the forward portion of the partition 7. The gases and sound waves are again divided by passage through the apertures 21 and their direction of flow is again reversed, said gases and sound waves moving rearwardly through the passageway 25 and passing through the curved passageway 27 to the passageway 26 whereby the direction of travel of said gases and sound waves is again reversed. The gases and sound waves pass from the passageway 26 through the multiplicity of apertures 22 formed through the partition 17, whereby they are again divided into a number of parts, said gases moving into the passageway 28 wherein their direction of travel is again reversed, and wherein various of the divided parts of the gases and sound waves are caused to travel longer distances than other parts thereof to reach the discharge end of the outlet element 5.

In the use of the improved muffler disclosed herein, the breaking up of the gases and the accompanying sound waves into many parts, and the forcing of the various divided parts of the gases and sound waves to travel various distances in the passageways 24 and 28, as has been explained, together with the repeated reversal of the direction of flow of said gases and sound waves, has a very effective silencing effect on the sound waves which causes the muffler to perform its intended function in a highly effective manner. Also, an important feature of the improved muffler which aids in the efficient performance of the function of the muffler is that wall portions of all of the passageways of the muffler through which the gases and sound waves pass are exposed to the outer atmosphere. As a result of this situation the exhaust impulses of the gases passing through the muffler are cooled and weakened during such passage of the gases. Additionally, because the lower portion of the outlet element 5 is in horizontal alignment with the lower portion of the passageway 28, as is shown in Fig. 2, moisture will be freely discharged from the muffler so that trapping of said moisture within the muffler is avoided. With regard to the apertures 20, 21, and 22 in the partitions 13, 7, and 17, respectively, it is pointed out that these apertures are of sufficient size so as to avoid production of excessive back pressure which would affect efficient operation of the engine with which the muffler is associated, and also, the apertures 20 and 22 of the partitions 13 and 17 are so disposed that location of a multiplicity thereof in any one vertical line is avoided.

I claim:

1. A muffler comprising an outer housing, and a plurality of partitions arranged within said outer housing which divide the interior of the muffler into a plurality of communicating passageways through which gases and sound waves accompanying said gases pass, there being a centrally located passageway which receives gases and sound waves entering the muffler, opposed intermediate passageways at opposite sides of said centrally located passageway, opposed outer passageways located outwardly of said intermediate

ate passageways from one of which gases are discharged from the muffler, and a connecting passageway which connects said outer passageways, the partition located between said centrally located passageway and one of said intermediate passageways, and the partition between the other of said intermediate passageways and the other passageway from which gases are discharged from the muffler each having a multiplicity of apertures formed therethrough which are distributed over a substantial surface portion thereof and through which gases and accompanying sound waves pass, and the partition between the other of said outer passageways and the adjacent intermediate passageway having apertures formed therethrough only adjacent to an end thereof, the arrangement and relation of said passageways and the disposition of the apertures of said apertured partitions being such that the direction of travel of gases and sound waves passing through the muffler is repeatedly reversed.

2. A muffler comprising an outer housing, and a plurality of vertically disposed partitions arranged within said outer housing which divide the interior of the muffler into a plurality of communicating passageways through which gases and sound waves accompanying said gases pass, there being a centrally located passageway which receives gases and sound waves entering the muffler, opposed intermediate passageways at opposite sides of said centrally located passageway, opposed outer passageways located outwardly of said intermediate passageways from one of which gases are discharged from the muffler, and a connecting passageway which connects said outer passageways, the partition located between said centrally located passageway and one of said intermediate passageways, and the partition between the other of said intermediate passageways and the outer passageway from which gases are discharged from the muffler each having a multiplicity of apertures formed therethrough which are distributed over a substantial surface portion thereof and through which gases and accompanying sound waves pass, and the partition between the other of said outer passageways and the adjacent intermediate passageway having apertures formed therethrough only adjacent to an end thereof, the arrangement and relation of said passageways and the disposition of the apertures of said apertured partitions being such that the direction of travel of gases and sound waves passing through the muffler is repeatedly reversed.

3. A muffler comprising an outer housing, and a plurality of vertically disposed partitions arranged within said outer housing which divide the interior of the muffler into a plurality of communicating passageways through which gases and sound waves accompanying said gases pass and which are arranged side by side in the transverse direction of the muffler, there being a centrally located passageway which receives gases and sound waves entering the muffler, opposed intermediate passageways at opposite sides of said centrally located passageway, opposed outer passageways located outwardly of said intermediate passageways from one of which gases are discharged from the muffler, and a connecting passageway which connects said outer passageways, the partition located between said centrally located passageway and one of said intermediate passageways, and the partition between the other of said intermediate passageways and the outer passageway from which gases

are discharged from the muffler each having a multiplicity of apertures formed therethrough which are distributed over a substantial surface portion thereof and through which gases and accompanying sound waves pass, and the partition between the other of said outer passageways and the adjacent intermediate passageway having apertures formed therethrough only adjacent to an end thereof, the arrangement and relation of said passageways and the disposition of the apertures of said apertured partitions being such that the direction of travel of gases and sound waves passing through the muffler is repeatedly reversed.

4. A muffler comprising an outer housing, and a plurality of vertically disposed partitions arranged within said outer housing which divide the interior of the muffler into a plurality of communicating passageways through which gases and sound waves accompanying said gases pass, there being a centrally located passageway which receives gases and sound waves entering the muffler, opposed intermediate passageways at opposite sides of said centrally located passageway, opposed outer passageways located outwardly of said intermediate passageways from one of which gases are discharged from the muffler, and a connecting passageway which connects said outer passageways, the partition located between said centrally located passageway and one of said intermediate passageways, and the partition between the other of said intermediate passageways and the outer passageway from which gases are discharged from the muffler each having a multiplicity of apertures formed therethrough which are distributed over a substantial surface portion thereof and through which gases and accompanying sound waves pass, and the partition between the other of said outer passageways and the adjacent intermediate passageway having apertures formed therethrough only adjacent to an end thereof, the arrangement and relation of said passageways and the disposition of the apertures of said apertured partitions being such that the direction of travel of gases and sound waves passing through the muffler is repeatedly reversed, and wall portions of said passageways being exposed to atmosphere exterior of the muffler whereby the exhaust impulses of gases passing through the passageways are cooled and weakened during passage of said gases through said passageways.

5. A muffler comprising an outer housing, and a plurality of vertically disposed partitions arranged within said outer housing which divide the interior of the muffler into a plurality of communicating passageways through which gases and sound waves accompanying said gases pass and which are arranged side by side in the transverse direction of the muffler, there being a centrally located passageway which receives gases and sound waves entering the muffler, opposed intermediate passageways at opposite sides of said centrally located passageway, opposed outer passageways located outwardly of said intermediate passageways from one of which gases are discharged from the muffler, and a connecting passageway which connects said outer passageways, the partition located between said centrally located passageway and one of said intermediate passageways, and the partition between the other of said intermediate passageways and the outer passageway from which gases are discharged from the muffler each having a multiplicity of apertures formed therethrough which are distributed

over a substantial surface portion thereof and through which gases and accompanying sound waves pass, and the partition between the other of said outer passageways and the adjacent intermediate passageway having apertures formed therethrough only adjacent to an end thereof, the arrangement and relation of said passageways and the disposition of the apertures of said apertured partitions being such that the direction of travel of gases and sound waves passing through the muffler is repeatedly reversed, and wall portions of said passageways being exposed to atmosphere exterior of the muffler whereby the exhaust impulses of the gases passing through the passageways are cooled and weakened during passage of said gases through said passageways.

6. A muffler comprising an outer housing, and a plurality of vertically disposed partitions arranged within said outer housing which divide the interior of the muffler into a plurality of communicating passageways through which gases and sound waves accompanying said gases pass and which are arranged side by side in the transverse direction of the muffler, there being a centrally located passageway which receives gases and sound waves entering the muffler, opposed intermediate passageways at opposite sides of said centrally located passageway, opposed outer passageways located outwardly of said intermediate passageways from one of which gases are discharged from the muffler, and a connecting passageway which connects said outer passageways, the partition located between said centrally located passageway and one of said intermediate passageways, and the partition between the other of said intermediate passageways and the outer passageway from which gases are discharged from the muffler each having a multiplicity of apertures formed therethrough which are distributed over a substantial surface portion thereof and through which gases and accompanying sound waves pass, and the partition between the other of said outer passageways and the adjacent intermediate passageway having apertures formed therethrough only adjacent to an end thereof, the arrangement and relation of said passageways and the disposition of the apertures of said apertured partitions being such that the direction of travel of gases and sound waves passing through the muffler is repeatedly reversed, and wall portions of all of said passageways being exposed to atmosphere exterior of the muffler whereby the exhaust impulses of the gases passing through the passageways are cooled and weakened during passage of said gases through said passageways.

7. A muffler comprising an outer housing, and a plurality of partitions arranged within said outer housing which divide the interior of the muffler into a plurality of communicating passageways through which gases and sound waves accompanying said gases pass, there being a centrally located passageway which receives gases and sound waves entering the muffler, opposed intermediate passageways at opposite sides of said centrally located passageway, opposed outer passageways from one of which gases are discharged from the muffler, and a connecting passageway which connects said outer passageways, the par-

tion located between said centrally located passageway and one of said intermediate passageways, and the partition between the other of said intermediate passageways and the outer passageway from which gases are discharged from the muffler each having a multiplicity of apertures formed therethrough which are distributed over a substantial surface portion thereof and through which gases and accompanying sound waves pass, and the partition between the other of said outer passageways and the adjacent intermediate passageway having apertures formed therethrough only adjacent to an end thereof, the arrangement and relation of said passageways and the disposition of the apertures of said apertured partitions being such that the direction of travel of gases and sound waves passing through the muffler is repeatedly reversed, and said gases and sound waves being divided into a great number of parts by passage thereof through said apertures and said divided parts being compelled to travel different distances after passing through said apertures to continue their passage through the muffler.

8. A muffler comprising an outer housing, and a plurality of partitions arranged within said outer housing which divide the interior of the muffler into a plurality of communicating passageways through which gases and sound waves accompanying said gases pass, there being a centrally located passageway which receives gases and sound waves entering the muffler, opposed intermediate passageways at opposite sides of said centrally located passageway, opposed outer passageways located outwardly of said intermediate passageways from one of which gases are discharged from the muffler, and a connecting passageway which connects said outer passageways, the partition located between said centrally located passageway and one of said intermediate passageways, and the partition between the other of said intermediate passageways and the outer passageway from which gases are discharged from the muffler each having a multiplicity of staggered apertures formed therethrough which are distributed over a substantial surface portion thereof and through which gases and accompanying sound waves pass, and the partition between the other of said outer passageways and the adjacent intermediate passageway having apertures formed therethrough only adjacent to an end thereof, the arrangement and relation of said passageways and the disposition of the apertures of said apertured partitions being such that the direction of travel of gases and sound waves passing through the muffler is repeatedly reversed.
